FIBER SPINNING APPARATUS

Vicente Aldaba, Manila, P. I.; vested in the
Alien Property Custodian

Application July 18, 1941, Serial No. 403,030

7 Claims. (Cl. 57—28)

This invention relates to a spinning apparatus for various fibers, for instance, manila hemp, sisal and maguey.

It is particularly aimed to provide a novel, efficient and durable machine which dispenses with the drawing operation incidental to the spinning of the fibers and reduces to a minimum the mechanisms or instrumentalities needed to spin the yarn.

It is further aimed to provide such a machine as will grip the fibers at a source of supply, feed the same to a spinner, and then wind the same, the construction being such that the amount of labor and power incidental to spinning is reduced to a minimum.

The more specific objects and advantages will become apparent from a consideration of the description following taken in connection with the accompanying drawings illustrating an operative embodiment.

In the drawings,

Figure 1 is a view of the apparatus in plan;

Figure 2 is a view in side elevation of the machine;

Figure 3 is a fragmentary plan view of the feeding belt;

Figure 4 is a cross section taken on the line 4—4 of Figure 3.

Figure 5 is an elevation looking toward the outlet end of the spinner;

Figure 6 is a central longitudinal sectional view of the spinner taken on the plane of line 6—6 of Figure 5;

Figs. 7 and 8 are detailed vertical sections taken substantially on the lines 7—7 and 8—8 of Fig. 1.

Figure 9 is a central longitudinal sectional view taken through a modified form of spinner;

Figure 10 is an elevation of a modified form of feeding mechanism; and,

Figure 11 is a fragmentary partial plan and section of the latter.

Referring specifically to the drawings wherein like reference characters designate like or similar parts throughout the different views, attention is called to the fact that the frame work of the apparatus, for the most part, has been omitted in the interest of clarity, it being obvious that the various parts or elements can be mounted or supported in various ways.

Fibrous strands are disposed in parallelism in a hopper, generally designated 10. Such fibers are usually handled in bundles as they come from a decorticating machine or as it is bundled by the retters. A hopper 10 is arranged in line with an endless feeding belt 11, of suitable flexible material, which traverses pulleys 12 and 13, carried by shafts 14 and 15, respectively, journaled in suitable bearings 16 and 17, respectively. Hopper 10 is located at one end of the feed belt 11,

as shown, but it may be located over the feed belt, or otherwise, as preferred.

Pickers or grippers 18, of any desired number, are carried by the flexible belt 11 and are best detailed in Figures 3 and 4. Such pickers or grippers comprise plates 19, which are riveted, at 20, to the belt and which have stationary jaws 21 rising therefrom. Jaws 22 are pivoted, at 23, to the jaws 21 and such jaws are urged into contact by contractile coil springs, at 24, fastened to jaws 22 and plates 19, at reversely curved terminals 25 providing sufficient space 26, for reception, gripping and retention of the fibrous strands, as the belt 11 moves into and out of the hopper 10. It will be noted that the forward end of hopper 10 (Figure 1) is open so as to provide clearance for operation and one wall or part in the hopper, at 27, is so located that it will be engaged by the outer or free end of trip levers 28, pivoted at 29, to plates 19, and bearing against the jaws 22 at the opposite side thereof to a spring 24, so as to open the jaws, receive the fibrous strands therein, grip them and convey them in parallelism to each other and to the sides of the belt 11. The jaws 22 and levers 28 will return to normal position under urgency of springs 24 when levers 28 disengage hopper part 27.

Belt 11 is located centrally over and travels in parallelism with the longitudinal axis of a vertically disposed V-shaped aligning trough 30, which is open at the front and rear. When the pickers 18 are at the lower run of the belt 11 and, thus, over the aligning trough 30, the fiber strands are released through the contact of the aforesaid levers 28 with an abutment 31 (Figure 2) suitably mounted on one side wall of the aligning trough 30. The released fibers thus fall to the bottom of the trough 30 and are in parallelism longitudinally thereof.

Disposed in front of the aligning trough 30 is a spinner, generally designated 32, the same having a central longitudinal bore 33 located in line with the junction of the inclined walls of the aligning trough so as to receive fibers from the latter, guided by a funnel-shaped or flared space 34 at the rear end thereof. Spinner 32 is journaled in a bearing 35 at a reduced portion 36 thereof. Adjacent the front, spinner 32 is enlarged into a pulley 37 having a belt receiving groove 38.

Located centrally at the front end of and attached to the spinner 32 is a generally round head 39 having an outlet orifice 40 for the yarn received from bore 33 and which is interiorly flared or recessed, at 41, to better guide the yarn to the orifice 40.

As best shown in Figure 5, orifice 40 is semi-circular. Across one side thereof is a straight edge constituting the outer extremity of an in-

clined fiber engaging wall 42 of a flap or block 43 disposed in recess 41, hinged to the head 39, at 44, and urged into the recess 41, as shown in Figures 5 and 6, by a spring finger 45 fastened, at 46, to the head 39.

In starting operation, a piece of yarn consisting of fibers in spun relation is disposed at the bottom of the aligning trough 30 and threaded through the spinner 32, passing through bore 33, enlargement 34, recess 31, and orifice 40. Such yarn will be spun as the spinner 32 rotates and as it emerges from the orifice 40, will be pressed against by the forward edge of wall 42, under suitable pressure regulated by spring 45, the rotation of the spinner serving to twist all fibers upon drawing thereof through the orifice. Spun yarn is indicated at Y.

It should also be mentioned that the starting piece of yarn threaded through the spinner or the yarn after sufficient drawing and spinning is passed through an eyelet 47 mounted by a collar 48 on a reciprocatory traverse rod 49 and is then connected to a reel or bobbin 50, for winding of the latter, as will be later specifically described.

The machine may be operated from any suitable source of power; for instance, an electric motor, indicated at 51, which, through the medium of a belt 52, traversing a pulley 53, keyed to a longitudinal shaft 54, drives the latter. Shaft 54 is disposed at a right angle to the traverse rod 49 and is journaled in any desired number of suitable bearings like that at 55. On shaft 54, a pulley 56 is fast and it is traversed by a belt 57, also traversing the spinner pulley 37 at the groove 38 thereof, in order to rotate the spinner.

On the forward end of the shaft 54 is a double worm 58 enmeshed with a worm wheel 59 fast on a horizontal shaft 60 suitably journaled in bearings 61. Keyed on shaft 60 are friction rolls 62 and 63. The feed belt 11, specifically the shaft 14 associated therewith, is driven or rotated from the shaft 60 through the medium of an endless belt 64, traversing pulleys 65 and 66 on shafts 60 and 14, respectively, such belt 64 being guided and tensioned by an auxiliary pulley, as at 67.

Removably and loosely mounted for vertical sliding in the aforesaid bearings 61, resting on the rolls 62 and 63 for rotation on an axis parallel to that of the shaft 60, are the aforesaid bobbin or reel 50 and a similar aligned bobbin or reel 69, respectively. Such bobbins are carried by individual shafts 70 and 70', loosely journaled in the bearings 61, the bobbins 50 and 69, respectively, having end plates 71 and 72, overlapping the ends of the rolls 62 and 63, so that bobbins 50 and 69 are resting on and always in contact with rolls 62 and 63. Through frictional contact with rolls 62 and 63, the bobbins 50 and 69 are rotated. In this way, as bobbins 50 and 69 increase in circumference through constant addition of yarn on the bobbins, the speed of any point on the surface of the bobbins is kept constant since it depends on speed of rotation of rollers 62 and 63. Thus, the speed of collecting the yarn by the bobbins from the spinner is constant and the number of twists per inch of the yarn is also kept constant.

On the aforesaid shaft 70', to which bobbin 69 is rigidly attached, a pinion 73 is keyed which is enmeshed with a gear wheel 74 keyed to a short shaft 75, suitably journaled at its ends in bearings 76. The teeth and meshes of pinion 73 and gear wheel 74 are of such depth as to remain

enmeshed notwithstanding the fact that shaft 70' must rise and fall. Also, keyed on shaft 75 is a pinion or gear 77 enmeshed with a gear 78 keyed to a shaft 79 journaled in suitable bearings at 80. On one end of shaft 79, a pinion 81 is keyed which is enmeshed with a relatively large gear wheel 82 keyed to a shaft 83, aligned with the short shaft 75 journaled at one end in the adjacent bearing 76 and at the other end in a bearing 84.

Fixed on the shaft 83 to rotate therewith is a relatively large cam wheel 85 which is generally diagonally disposed and which peripherally has a groove 86, into one end of which the traverse rod 49 extends at a dependent or roller 87, so that rotation of the cam member 85 through rotation of gear wheel 82 will reciprocate the traverse rod 49. It should be stated that traverse rod 49 is non-rotatable because of the engaged dependent 87 in groove 86, but it is also preferably non-circular in cross section as well as slidably mounted in one or more supports or bearings, as at 88.

A regulating or drag reel is provided at 89, having a shaft or trunnions 90 loosely journaled in bearings 91. A control cord 92 wound on the reel or drum 89, passes through an eyelet 93 on the collar 94 carried by traverse rod 49 and one end of which cord 92 is fastened to the bobbin 69.

Since cord 92 is of the same count or size as the yarn spun by spinner 32, bobbin 69 grows in diameter or circumference at the same rate as bobbin 50. As bobbin 50 grows in diameter, its rotation becomes slower because it is run by frictional contact with roll 62.

In order to maintain even distribution of yarns on the bobbin, the distribution rod 49 must slow down in its traverse motion at the same rate as the slowing down of the rotation of bobbin 50. This is accomplished by bobbin 69, which winds cord 92 at the same rate as bobbin 50 winds the spun yarn and thus grows in diameter at equal speed. Since pinion 73, which is keyed to the shaft 70' rigidly attached to bobbin 69, runs the train of gears which run the cam 85 that runs the distribution rod 49, the traverse speed of rod 49 naturally slows down as the bobbin 69 grows in diameter.

The parts are so constructed and timed in operation that the spun yarn produced is wound on the drum 50 evenly throughout the length thereof and in reverse directions in layers due to the reciprocation of the traverse rod 49 under motion imparted by the cam wheel 85. The cord 92 is of the same size or count as the yarn being spun at Y, and the winding occurs on both bobbins 50 and 69 at the same rate and to the same extent so that the rate of traverse and revolution or rotation of the bobbins 50 and 69 is maintained at a constant ratio so that the distribution of yarn Y on bobbin 50 is kept even.

It will be clear that the number of twists imparted to the yarn Y is regulated by the relative speed of the spinner 32 and the relative speed of the shaft 60. The size of the yarn is governed by the length of the fibers used, the speed of the endless belt 11 and the capacity of the picker or grip members 18.

Various changes may be resorted to provided they fall within the spirit and scope of the invention, for instance, in Figure 7 a different or modified type of spinner is illustrated. This spinner is generally designated 32', and is mounted in the machine in the same relation as the spinner 32, in order to have the yarn Y pass

through a bore 33' therein, which bore at the receiving end is flared, as at 34', and also preferably flared at the outlet end, as at 95, although this end may be of the same diameter as the major portion of the bore and the spinner at such end have the parts 39 and 46 applied thereto, as in the spinner 32. It will be particularly noted, however, that the intermediate portion of spinner 32' is crooked or deflected, as at 96, in order to enhance the spinning function when the spinner is rotated. This spinner 32' at one end has a head or enlargement 97 adapted to be journaled in a suitable bearing and at the other end has a head or enlargement 98 grooved at 99 to provide a cylindrical surface to be journaled in a suitable bearing. Such head 98 also has a groove at 100, in effect converting it into a pulley for reception of a drive belt, such as 57 in the preceding form.

In Figures 8 and 9, I have suggested another or modified form of fiber feeding mechanism, which may be used in place of the belt 11 and the grippers 18 associated therewith. In this modified form, a belt 11' of leather or other suitable material is trained over pulleys 12' and 13', located and functioning like those at 12 and 13, respectively, in the previous form. It will be clear that the pulleys 12' and 13' are mounted and operated in the same manner as those at 12 and 13, respectively, in relation to the hopper 10, so that pickers 18', carried by the belt 11', will function to feed the fibers to the spinner 32 or 32' in the same manner and relation. Such pickers or grippers 18' supplant those at 18 and each may consist of a metallic or other plate 101, pivoted or otherwise secured as at 102 to the belt 11'. Each plate 101 has a stud or the like 103 integral or rigid therewith whose outer end is beveled or chamfered, as at 104, in order to better align the fibers for gripping. Gripper rods 105 are slidably mounted transversely of the plates and centrally and longitudinally of the studs 103 and at their outer ends have heads 106 which are urged toward the surfaces 104 in order to grip a bundle of parallel fibers, as at F. The bores or openings in which said gripper rods 105 slide are enlarged into recesses 107 intermediate their ends and in such recesses expansive coil springs 108 are disposed which abut an end wall of the recesses and a nut or other abutment 109 applied to the rods within the recesses. Attention is called to the fact that the rods 105 are of such length that when the heads 106 are engaged with the studs or grip fibers the rods extend inwardly beyond the inner surface of the belt 11'. As a result, when the rods 105 at their inner ends engage the pulley 13', they will be projected outwardly against the tension of the springs 108 and thus open the grippers by moving heads 106 away from surfaces 104. As the grippers extend downwardly and forwardly in the direction of the arrow in Figure 8, they engage the bunches of fibers in the trough or hopper and as they gradually disengage the pulley 13', they close, that is, the heads 106, in combination with surfaces 104, will grip such fibers and convey them to the spinner, due to the expansion of springs 108, releasing them into the hopper 30 when the inner ends of the gripper rods 105 contact the periphery of the pulley 12', which opens the grippers and the fibers fall therefrom.

I claim as my invention:

1. In apparatus of the class described, positively driven means, two reels frictionally driven by the latter, means mounting said reels for movement radially with respect to the axis of rotation

5 of said positively driven means, a traverse rod, means operable by one of said reels to reciprocate the traverse rod, follower eyelets on said rod, one of the eyelets being located for passage of spun yarn therethrough to one of said reels, a roll having a cord thereon, said cord passing through the other eyelet and being connected to the other reel.

10 2. Spinning apparatus comprising a spinner to receive fibers, reeling means to receive yarn from the spinner, means mounting the reeling means for rotation and sliding transversely with respect to the axis of rotation as the winding of yarn on the reeling means increases, a reciprocatory traverse mechanism through which the said yarn passes located between the spinner and reeling means, means to rotate the reeling means and reciprocate the traverse mechanism, and drag means interconnected with the traverse mechanism to maintain the rate of traverse and revolution at a constant ratio.

15 3. Spinning apparatus comprising a spinner to receive fibers, reeling means to receive yarn from the spinner, a positively driven member on which the reeling means rests for rotation by friction and for sliding in a direction away from the axis of rotation of the reeling means as the winding of yarn on the latter increases, a reciprocatory traverse mechanism through which the yarn passes, means to rotate the positively driven member and reciprocate the traverse mechanism, and drag means interconnected with the traverse mechanism to maintain the rate of traverse and revolution at a constant ratio.

20 4. Spinning apparatus comprising a spinner to receive fibers, positively driven means, two reels bodily movable to and from the axis of rotation of the driven means and resting on the driven means and frictionally rotated thereby, a traverse rod, means to reciprocate the traverse rod, said rod having eyes, one of said eyes being located for passage of spun yarn therethrough to one of said reels, and a drag roll having a cord thereon, said cord passing through the other eye and being connected to the other reel.

25 5. Spinning apparatus comprising a spinner to receive fibers, positively driven means, two reels resting on said driven means so as to be frictionally rotated thereby, means mounting said reels for independent sliding relatively to the axis of rotation of the driven means, a reciprocatory traverse rod interengaged with yarn passing from the spinner to one of the reels, and drag means to maintain the rate of rotation of the positively driven means and the rate of traverse of said rod at a constant ratio interconnected with said traverse rod and the other reel.

30 6. Spinning apparatus having a rotatable spinner arranged to receive fibers, a driven shaft, roll means having a shaft, means to drive the latter from the driven shaft, means to drive the spinner from the driven shaft, reels slidably relatively to the axis of rotation of the roll means resting on and frictionally driven by the latter, a traverse rod provided with means through which spun yarn passes to one of the reels, drag means interconnected with said rod and connected to the other reel, and means to reciprocate the traverse rod operable from the driven shaft.

35 7. Spinning apparatus according to claim 6 in which the last mentioned means includes a gear, a shaft for said gear, a wheel on the latter shaft having a cam groove, and said traverse rod having a part engaged in said cam groove.

VICENTE ALDABA.
